The ornamental design for a display screen with animated graphical user interface, as shown and described.

DESCRIPTION

FIG. 1 is a front view of a display screen with animated graphical user interface showing a first image of the claimed design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The broken lines show an outer portion of the display screen to illustrate the environment of the claimed design and form no part of the claimed design.

The appearance of the animated images sequentially transitions between the images shown in FIGS. 1-7. The process or period in which one image transitions to another, including any intermediate images, forms no part of the claimed design.
